UNITED STATES PATENT OFFICE.

LOUIS PH. BOLANDER, OF SAN FRANCISCO, CALIFORNIA.

COUNTERBALANCED FLAGPOLE.

Application filed March 2, 1926. Serial No. 91,855.

The invention relates to a counterbalanced flag pole.

The object of the present invention is to improve the construction of counterbalanced flag poles and to provide a simple, practical and efficient counterbalanced flag pole of strong, durable and comparatively inexpensive construction adapted to be mounted in a variety of ways either in the ground or 10 upon a building or other structure and capable of being readily lowered from a vertical to a horizontal position for renewals at the top and for repainting, thereby insuring preservation and lasting qualities and at 15 the same time eliminating dangerous climbing of the pole.

A flag pole when installed may be straight and afterwards become sprung or crooked and it is the object of the invention to equip 20 the counterbalanced flag pole with means for plumbing the pole both in the direction of the pivotal movement of the pole and at right angles to the same to enable the pole to be maintained in a true perpendicular 25 position.

Another object of the invention is to provide a construction of counterbalanced flag pole which will permit a free circulation of air around the pole and the means for 30 mounting and adjusting the same.

With these and other objects in view the invention consists in the construction and novel combination and arrangement of parts hereinafter fully described, illustrated in the 35 accompanying drawings and pointed out in the claims hereto appended, it being understood that various changes in the form, proportion and minor details of construction, within the scope of the claims, may be 40 resorted to without departing from the spirit or sacrificing any of the advantages of the invention.

In the drawings:—

Figure 1 is an elevation of a counterbalanced flag pole constructed in accordance 45 with this invention.

Fig. 2 is a vertical sectional view of the same.

Fig. 3 is a horizontal sectional view taken 50 substantially on the line 3—3 of Fig. 2.

Fig. 4 is an enlarged horizontal sectional view taken substantially on the line 4—4 of Fig. 2.

Fig. 5 is a horizontal sectional view taken 55 substantially on the line 5—5 of Fig. 2.

Fig. 6 is a detail vertical sectional view taken substantially on the line 6—6 of Fig. 4.

Fig. 7 is a perspective view of the counterbalanced flag pole with the hinged channel sections in an opening position and the pole 60 lowered.

In the accompanying drawings in which is illustrated the preferred embodiment of the invention 1 designates a pivotally mounted pole designed to be constructed of wood or any other suitable material and provided adjacent to its lower end with a horizontal opening 2 through which passes a horizontal shaft or pivot 3 projecting laterally from opposite sides of the pole and having its terminals 4 arranged in bearing recesses 5 of adjustable bearing blocks 6. The pole is equipped at opposite sides at the ends of the opening 2 with closure plates 7 preferably of rectangular form and arranged in recesses 8 in the side faces of the pole in flush relation with the said side faces as clearly illustrated in Fig. 4 of the drawings. The plates 7 are provided with openings 9 the walls of which tightly fit the shaft or 80 pivot 3 and form bearings and the said plates are adapted to exclude moisture from the interior of the pole at the opening 2. By this construction the pole is prevented from rotting or deteriorating at the opening 2 and the life of the pole is materially increased. The plates 7 are secured to the pole by transverse pins 10 piercing the pole and the plates and secured to the latter by being headed in countersunk openings in the 85 plates but any other suitable fastening means may, of course, be employed as will be readily understood. The side faces of the pole are spaced from the adjacent bearings 6 by means of collars 11 arranged on the 90 ends of the horizontal pivot 3 and interposed between the pole and the adjustable bearing blocks as clearly shown in Fig. 4. The horizontal pivot 3 permits the pole to swing 95 from a vertical position to a horizontal position for repainting and for renewing the top of the pole or similar purposes and access is thus afforded to all portions of the pole without the danger and inconvenience of climbing the same.

The bearing blocks 6 are arranged in spaced vertically disposed channel bars or members 12 and they are tapered to fit the inner side faces of conventional channel members 12 as clearly shown in Fig. 4 but 105 110

the channel members and the adjustable bearing blocks 6 may be of any other desired configuration. By fitting snugly the walls of the channels 13 the adjustable bearing blocks 6 are firmly pressed against horizontal movement in an outward direction and also longitudinally of the bearing blocks which are securely clamped in the channels 13 by means of screws 14 provided at their inner ends with heads and having outer threaded ends engaging threaded openings in the web or connecting portions of the channel members. The adjustable bearing blocks 6 are provided with vertical slots 15 through which the screws 14 pass and washers 16 are preferably interposed between the heads of the screws and the inner adjacent side faces of the bearing blocks to afford relatively large clamping faces. The slots 15 permit a limited vertical adjustment of the bearing blocks and when the screws 14 are loosened this adjustment is accomplished by means of vertical adjusting screws 17 mounted in vertical threaded openings 18 in the bearing blocks and arranged in pairs and located at opposite sides of the ends 4 of the horizontal pivot 3. The screws 14 and 17 are provided with polygonally arranged receiving heads to be readily turned to effect an adjustment of the bearing blocks. By raising and lowering the adjustable bearing blocks 6 the pole may be trued or plumbed in a direction at right angles to the pivotal or swinging movement of the pole and the plumbing of the latter in the direction of the swinging or pivotal movement is effected by means of opposite adjusting devices mounted on horizontal connecting bars 19 and 20 secured at their terminals to the flanges of the channel members at the outer faces thereof as clearly illustrated in Fig. 5 of the drawings. The adjusting means are located adjacent the lower end of the pole and the connecting bar 19 may be riveted to the channel members as indicated at 21 in Fig. 5 while the connecting bar 20 is detachably secured to the channel members by screws 21 which permit the connecting bar 20 with its adjusting device to be removed from the channel members when it is desired to swing the pole from a vertical to a horizontal position. The adjusting device carried by the connecting bar 19 consists of a screw 22 at one end and provided with a lock nut 23. The adjusting screw 22 passes through a threaded perforation in the connecting bar 19 and the lock nut engages the outer face thereof. The screw 22 forms an adjustable abutment for the pole and limits the swing of the lower portion in one direction. The adjusting means carried by the connecting bar 20 consists of an adjusting screw 25 mounted in a threaded perforation of the connecting bar 20 and abutting at its inner end against the pole. The screw 25

will tend to force the lower portion of the pole in the direction of the connecting bar 19 and will cooperate with the adjusting means thereof in maintaining the pole firmly in its adjusted position. The adjusting screw 25 is provided with a lock nut 26 which abuts against the outer face of the connecting bar 20. The inner end of the adjusting screw 22 and 25 abut against the plates 41 of the pole and they do not interfere with the vertical adjustment of the pole. Any number of the adjusting screws 22 and 25 may be employed.

The horizontal adjusting screws are adapted to true or plumb the pole in one direction and the vertical adjusting screws in a direction at right angles to the pole adjustment of the horizontal screws. The vertical adjusting screws which extend entirely through and project below the vertically adjustable bearing blocks have their lower ends arranged in seats 27 consisting of circular recesses formed in the upper faces of stationary supporting blocks 28 conforming to the configuration of the channels of the vertical members 12 and secured in the said channels by rivets 29 or other suitable fastening devices. The supporting blocks 28 are located below the bearing blocks and provide rigid supporting means for the lower ends of the adjusting screws as clearly illustrated in Fig. 6 of the drawings.

The vertical channel members 12 which constitute the main supporting means for the pivot of the pole are connected by upper and lower horizontal connecting bars 30 and 31. The upper connecting bar 30 is located at the same side of the pole as the connecting bar 19 and the lower portion of the pole swings away from the connecting bar 30 in the operation of lowering the pole to a horizontal position and the said upper bar 30 is located at sufficient distance below the horizontal plane of the pivot so as not to interfere with the swinging movement of the pole in the raising and lowering movements. The lower connecting bars 31 are located below the lower end of the pole and the counter-balancing means hereinafter described and do not interfere with the swinging movement of the pole. Any number of the connecting bars may be employed and they may be arranged in any suitable manner which will not interfere with the pivotal or swinging movement of the pole.

The spaces between the vertical members 12 are closed at opposite sides thereof by vertical hinged channel members 32 each connected at one of its side flanges by suitable hinges 33 to one of the channel members 12 and arranged to abut against the other channel member when in closed position as illustrated in Fig. 4 of the drawings. The hinged channel members 32 are adapted to be swung open to afford access to the lower

portion of the pole and they are held in closed position by detachable ornamental base members 34. The base members 34 which fit against the lower portions of the hinged channel members are provided with laterally extending flanges 35 which are detachably secured to stationary base members 36 by screws 37 which are mounted in suitable threaded openings in the stationary base members 36. When it is desired to adjust the pole or lower the same to a horizontal position the detachable base members are removed and the hinged channel members are open. This will afford access to the interior. The stationary and detachable base sections are provided with ornamental top portions 38 and are also preferably of an ornamental character and the upper ends of the hinged and stationary channel members 32 and 12 are provided with ornamental cap pieces 39. The channel members and the base sections may be ornamented in any desired manner and the channel structure will afford a free circulation of air through the device and around the pole and the adjusting means for the same.

The pole is counterbalanced by means of a counterbalancing weight composed of a plurality of similar metal plates 40 fitted flat against each other and arranged with their flat faces in a vertical position as clearly shown in Fig. 2 of the drawings. The plates 40 are connected together and are also secured to hanger plates 41 by means of horizontal rods or bolts 42 preferably arranged in pairs as shown and piercing the weight members or plates 40 and also the hanger plates 41. The hanger plates 41 are secured to the pole at opposite sides thereof preferably in recesses of the pole with their outer faces in flush relation with the adjacent faces of the pole as clearly shown in Fig. 2 of the drawings. These plates 41 extend below the lower end of the pole and the lower edges of the plates 40 which are arranged between and also at the outer sides of the hanger plates 41. Any number of the weight members or plates 40 may be used to properly counterbalance the pole and they will enable the pole to be easily swung on its pivot 3 to lower the pole from a vertical position to a horizontal position and to return it to its vertical position.

The pole support may be mounted in the ground in a concrete base or upon a building or any other structure and may be supported and braced in any other desired manner as will be readily understood and the vertical members and the base sections will present an ornamental and attractive support for the pivoted pole.

What I claim is:

1. A device of the class described comprising a support, a pole having a pivot

mounted upon the support and arranged to permit the pole to swing from a vertical to a horizontal position and means for adjusting the pole in the direction of its pivotal movement and separate means for adjusting the pole at right angles to the direction of its pivotal movement. 70

2. A device of the class described including a support having spaced fixed supporting members, a pole pivotally mounted between the supporting members, hinged members closing the space between the fixed members and means for detachably securing the hinged members in their closed position. 75

3. A device of the class described comprising a support composed of fixed vertical members spaced apart and provided with bars, a pole having a pivot mounted in the bearings, hinged vertical members closing the space between the fixed vertical members and detachable base sections securing the hinged members in their closed position. 80

4. A device of the class described comprising a support composed of fixed vertical members spaced apart and provided with bars, a pole having a pivot mounted in the bearings, hinged vertical members closing the space between the fixed vertical members and stationary and detachable base sections mounted respectively at the lower portions 90 of the fixed and hinged members and detachably securing the hinged members in their closed position. 95

5. A device of the class described including spaced vertical members, bearing blocks 100 carried by the vertical members and provided with spaced vertical adjusting screws for raising and lowering the bearing blocks, a pole having a pivot mounted in the bearing blocks and separate means for securing 105 the bearing blocks in their vertical adjustment.

6. A device of the class described including vertical channel members, stationary supporting blocks secured in the channels 110 of the members, adjustable bearing blocks arranged in the channels of the members and provided with bearing recesses, a pole having a pivot mounted in the bearing recesses of the bearing blocks and means supported 115 on the fixed blocks for raising and lowering the bearing blocks.

7. A device of the class described including vertical channel members, stationary supporting blocks secured in the channels of 120 the members, adjustable bearing blocks being provided with vertical slots and fastening devices operating in the slots for clamping the bearing blocks in their adjustment.

8. A device of the class described comprising vertical members, stationary supporting blocks mounted on the said members, bearing blocks provided with bearing recesses, vertical adjusting screws mounted in the bearing blocks and supported upon the fixed 125 130

- blocks for raising and lowering the bearing blocks, said bearing blocks being provided with vertical slots, fastening devices operating in the vertical slots for clamping the same in their adjustment and a pole having a pivot arranged in the said bearing recesses. 9. A device of the class described including a vertical member, fixed supporting blocks secured to the said members and provided in their upper faces with seats, adjustable bearing blocks guided by the said members and located above the fixed blocks and having threaded openings, vertical adjusting screws mounted in the threaded openings and having their lower ends fitted in the said seats, a pole having a pivot journaled on and carried by the bearing blocks and means for clamping the bearing blocks in their adjustment. 10. A device of the class described including a support having spaced vertical members, a pole having a pivot mounted upon the support, a connecting member extending across the space between the members and an adjusting device located below the pivot and mounted on the connecting bar for adjusting the pole to maintain the same in a vertical position. 11. A device of the class described including a support having spaced vertical members, a pole having a pivot mounted upon the support, connecting members secured to the vertical members, screws mounted on the connecting members and engaging the pole at opposite sides of the same. 12. A device of the class described including a support having spaced vertical members, a pole having a pivot mounted upon the support, connecting members secured to the vertical members, screws mounted on the connecting members and engaging the pole at opposite sides of the same, one of the adjusting devices being detachable to permit the pole to swing to and from a vertical position.

In testimony whereof I have hereunto set my hand.

LOUIS PH. BOLANDER.
